UNITED STATES PATENT OFFICE

BURT F. UPHAM, OF BOSTON, MASSACHUSETTS, ASSIGNOR TO MILLER PRINTING MACHINERY COMPANY, OF PITTSBURGH, PENNSYLVANIA, A CORPORATION OF PENNSYLVANIA

SHEET SEPARATING DEVICE

Application filed November 27, 1929. Serial No. 410,219.

My invention pertains to sheet separating devices, and particularly to devices in which the top sheet is separated from a pile of sheets by being lifted vertically therefrom, as by 5 means of a plurality of pneumatic separator feet operating on the sheet adjacent the front edge of the latter.

Sheet separating devices of the above character have been refined to such an extent that 10 they are highly efficient in effecting the desired result of lifting one sheet, and one sheet only, from the pile at each operation. However, the difficulty does sometimes occur, particularly when paper stocks of an especially 15 difficult character have to be separated, that two or more sheets are lifted from the pile, and consequently carried forward by associated devices of the printing press feeder or other machine in connection with which the 20 separator device is employed, instead of one sheet only being lifted. It is the principal object of my invention to improve, in this respect, upon prior sheet separating devices of this character, and to provide a separating 25 device in which the lifting of more than one sheet will be still further insured against.

My invention may be embodied in numerous constructional forms, without exceeding the scope thereof as defined in the appended 30 claims. By way of example, one such form is described in the following specification and shown in the accompanying drawing, in which Fig. 1 is a partly sectional side view of the device, and Fig. 2 is a detail view of a 35 portion of the device as seen from the line II-II of Fig. 1.

A sheet separating device of well known form, to which my invention is applicable, comprises a stock table 10 for carrying a pile 40 of sheets, such, for instance, as the pile of blank paper intended for automatic feeding into a printing press. Such a table is ordinarily provided with automatic mechanism for raising it gradually as the sheets are 45 moved one by one from the pile of sheets carried thereby, so that the top of the pile is maintained at a constant level. The pile of sheets is maintained in proper position upon the stock table by means of a pair of side 50 front stakes 11, and usually by a pair of side

stakes (not shown). A rear stock guide is also usually employed for confining the pile in a roughly correct position with respect to the front stakes. Such a device further includes a separator bar 12 arranged for vertical movement, as by means of plungers 13, provided at the end of the bar, which enter suitable guides 14 formed in the side frames 15 of the device. From the separator bar depend a plurality of stems 16 the lower ends 55 of which carry pneumatic separator feet 17, which are connected, as by hose 18, with the interior of the separator bar 12, the latter being hollow and having a connection 19 with a suitable suction pump. A rock shaft 60 20 is oscillatably mounted in the frame 15, and has levers 15a thereon the front ends of which are forked to embrace the separator bar 12. Thus rocking movements of the shaft 20 cause downward and upward movements 65 of the separator feet 17. Upon these feet reaching or approaching their lowermost position, a valve is actuated to apply suction, whereby the top sheet of the pile becomes attached thereto. When the separator 70 feet rise, they carry the top sheet of the pile with them, and sustain it in position to be taken away by feed members forming part of the mechanism with which the separating device is employed. 75

According to my invention, I provide upon the front stakes 11, small lips or projections 21 which extend a slight distance inwardly towards the pile of sheets so that the front edges of the sheets must brush past these 80 projections in being raised by the separator feet 17. These lips or projections may conveniently be constituted by relatively small wires (Fig. 2) passing through holes drilled in the front stakes and secured therein so 85 that the parts which extend from the operative faces of the front stakes are disposed in a horizontal position. In association with the projections 21, and in proximity with the front stakes, I provide a plurality of 90 blower pipes 22 the nozzles 23 of which are elongated and disposed vertically in such a position that the blast from the pipes will be directed both below and above the projections 21. These blower pipes are con- 95 100

nected with a suitable blower in such a manner that the blast of air issues substantially continuously therefrom.

In order to insure the fair engagement of the front edges of the top sheets of the pile with the front stakes 11, and thereby insure the proper operation of the projections 21, I provide means for combing the top sheets continuously towards the front stakes 11. Such combing means comprises a plurality of comber blocks 24 (preferably two in number) of substantial weight, through the top parts of which blocks passages 25 are formed for the reception of cords 26. These cords are secured upon the shaft 20 in such manner that their ends participate in the rocking movements of the latter. By this means a pull is intermittently exercised by the cords 26 upon the blocks 24, causing the latter to vibrate somewhat and comb the top sheets of the pile towards the front stakes 11. To this end, the blocks 24 are so adjusted on the cords 26 that they occupy a somewhat tilted position with respect to the rear corner of the pile.

In order that the position of the blocks 24 can be readily adjusted, especially for sheets of varying sizes, the blocks 24 are formed for the reception of screws 36 which pass upwardly therethrough and enter the passages 25 so as to exert a frictional pressure on the cords 26. This frictional pressure can be so adjusted that all that is necessary, in order to adjust the position of the blocks, to change their angle or apply them to sheets of different sizes, is to move them manually forward or backward on the cords 26. To assist the combing action and further insure the maintenance of the front of the pile against the stakes 11, the stock table 10 is inclined downwardly and forwardly, as shown.

In the operation of the device, the combing action of the blocks 24 results in the top few sheets of the pile being maintained fairly in engagement with the front stakes 11, beneath the projections 21. The blast of air issuing from the blower nozzles 23 enters between the top few sheets of the pile and causes a "fluffed" or air separated condition of such sheets, the top sheet being prevented from rising to an undesirable extent by the engagement of its front edge beneath the projections 21. Thus, when the separator feet 17 descend upon the top sheet, this sheet will normally already be separated by an air space from the sheet next succeeding it, so that the lifting of a second sheet is rendered unlikely. Upon the separator feet rising, the edge of the top sheet is forced to brush past the projections 21, with a resultant tendency of any following sheet to be brushed off and fall back upon the remainder of the sheets. As the separator feet rise to their topmost position the blast of air, issuing above the projections 21, is directed against the under side

of the separated and lifted sheet and causes a fluttering of the latter, which fluttering tends to displace a second sheet, should such a sheet have been lifted with the top sheet, and cause each second sheet to fall back on the pile.

By the improved separating device described above, I am enabled to separate efficiently grades of stock which have heretofore given much difficulty in the way of two or more following sheets being lifted with the top sheet, and I am enabled to separate stocks efficiently at higher speed than has heretofore been possible.

What I claim as new, and desire to secure by Letters Patent, is:—

1. A device for separating sheets singly from a pile thereof, comprising a sheet lifting member adapted to operate on the top sheet of the pile, means disposed in the path of the sheet being lifted by said member for engagement with the edge of such sheet, means for directing an air blast towards the pile both below and above said engagement means, and means for combing the top sheets of the pile towards said engagement means.

2. A device for separating sheets singly from a pile thereof, comprising guiding means for engagement by the front of the pile, a sheet lifting member adapted to operate on the top sheet of the pile adjacent the front of such sheet, means projecting with respect to said guiding means into the path of the sheets being lifted for engagement with the edges of such sheets, means for directing an air blast towards the pile both below and above said engagement means, and means for continuously combing the top sheets of the pile into close engagement with said guiding means.

In testimony whereof, I sign my name.
